UNITED STATES PATENT OFFICE.

JOHN W. PAGE, OF CHICAGO, ILLINOIS.

EXCAVATING DEVICE.

Application filed January 12, 1924. Serial No. 685,750.

To all whom it may concern:

Be it known that I, JOHN W. PAGE, a citizen of the United States, residing at Chicago, in the county of Cook and State 60
5 of Illinois, have invented new and useful Improvements in Excavating Devices, of which the following is a specification.

This invention relates to certain new and useful improvements in excavating devices, 10 and is fully described and explained in the specification and shown in the accompanying drawings, in which Fig. 1 is a view in side elevation, showing the bucket on the trolley, Fig. 2 is a similar view showing the 15 bucket in the position it occupies just after the sheave 18 has engaged the stop block 19, Fig. 3 is a similar view showing the bucket dumped, Fig. 4 is a view in front elevation of the sheave over which the holding chain 20 operates, and Figs. 5 and 6 are views in side elevation of the same sheave showing the holding chain in different positions.

The excavating device herein shown is of 25 the same general type as, and an improvement on, the excavating device shown in my Patent No. 1,194,777, dated August 15, 1916, and its general method of operation is substantially the same. The particular 30 features of difference between this device and the one shown in said patent will be particularly pointed out herein.

Referring to the drawings, 5 indicates a cableway provided with the usual means whereby it may be tightened and slackened. 35 This cableway is similar to one shown in my prior patent referred to above. The present device has been found particularly useful in excavating gravel pits and for similar purposes where it is sought to dump 40 the material for many successive bucket loads in a predetermined position, as in a hopper (not shown) arranged under the bucket as it dumps. The general arrangement of the trolley with respect to the 45 gravel pit and the location of the hopper, are all shown in my prior patent, above referred to, and consequently need not be shown here, since the operation of the device in respect to these features is substantially 50 the same as in said prior patent. The particular construction and operation of the device with respect to its dumping is however somewhat different and will be described in detail hereinafter. The inclination 55 of the cableway 5 is such that the bucket will run down by gravity to the

point at which it is sought to have it work, and therefore there is required no mechanism for hauling it in the backward direction in this particular instance.

Mounted upon the cableway 5 is a trolley which may be of any desirable form, here shown as a triangular frame 7 carrying grooved rollers or wheels 8 running upon the cableway. Attached to the underside 65 of the trolley is a bail 9, to which is swiveled an excavating shovel 10, the centers of the pivots preferably being behind the center of gravity of said shovel. The bail 9 may be of any suitable form and is here 70 shown as formed of two chains separated near their lower ends by means of the spreader bar 9'.

11 indicates the hauling chains, 12 is the holding chain thereof, and 13 is the loading 75 line or main hauling line, to which the holding chain 12 and the two hauling chains 11 are attached, as is common practice in the Page buckets now used for excavating 80 purposes.

In the device here shown the holding chain 12 runs over a block 15 attached to the trolley 7. The block 15 is attached to the underside of the trolley 7. Over this block runs the holding chain 12, the forward end of which is secured to the main 85 hauling line or loading line 13 by means of the link 13'. From this point it runs upwardly and backwardly over the block 15 and thence is led downwardly to the upper forward part of the bucket, where it is secured at the center as indicated by 14. The block 15 is provided with a double 90 grooved sheave 15', shown removed from the block in Fig. 4. The two grooves of this sheave are concentrically arranged, one being larger than the other. I have indicated the smaller groove by 76 and the larger groove by 77. The larger groove is 95 formed by the flanged discs 78 forming the sides of the sheave. The holding chain 12 carries at one point a lock bar 81. This bar is preferably made of a flat strip of metal bent as shown and thin enough so that it will pass between the discs 78 and run down on the smaller groove 76 (see Fig. 5). The rest of the holding chain 12 is large 100 enough so that it will not pass between the discs 78, but will run up on the larger groove 77 at the periphery of the discs 78 (see Fig. 4). The lock bar 81 is so placed in the chain 12 that when the bucket 105 110

is in its normal position, before it has commenced to dump (as shown in Fig. 1), said bar will be in the position substantially as shown in Fig. 5. When in this position it 5 will be noted that the locking bar 81 is in between the discs 78 resting on the smaller groove 76. This will give a leverage in favor of the end of the holding chain 12 attached to the end of the loading line or 10 main hauling line 13, so that but a slight tautness on said hauling line 13 will serve to maintain sufficient tension on the holding chain 12 to prevent dumping of the bucket. 15 16 indicates a sheave carried preferably near the point where the holding chain 12 joins the loading line 13. A rope 17 is connected to the holding chain 12 a slight distance above the bucket at the point indicated by the reference numeral 17'. From 20 this point the rope 17 runs under the sheave 16 and up to another sheave 18, which runs on the cableway 5. 19 indicates a stop block on the cableway at about the point where the dumping is to occur. 25 The operation of the device is as follows: As the bucket is drawn forward, the tautness maintained on the holding chain 12 by the pull of the hauling line 13 is sufficient to prevent the bucket from dumping. When 30 the sheave 18 strikes the block 19, the holding chain 12 is pulled from the point 17' over the sheave 16, as shown in Figure 2. When this occurs the holding chain 12 runs up on the larger groove of the sheave 35 16 and the locking bar 81 is pulled out of the sheave, thus destroying the locking effect of this locking bar. At this point, if tension is maintained on the main hauling line 13 the bucket is still prevented from 40 dumping. Such tension is transmitted through the rope 17 to the point 17' on the holding chain and the holding chain above this point is likewise exerting a pull upwardly and in the opposite direction so that 45 the component of the forces by the holding chain above the point 17' and the rope 17 exerts an upward pull on the short lower end of the holding chain below the point 17' to prevent the bucket from tilting or 50 dumping. When it is desired to dump the bucket, the hauling line 13 is slackened by the operator and this slackening releases the pull on the rope 17 and also on the holding chain 12 and permits the bucket to dump, 55 as shown in Figure 3.

It is to be noted that the position of the locking bar 81 on the smaller groove 76, as shown in Fig. 5, assists in preventing the dumping of the bucket, since in this 60 position it gives a leverage in favor of the end of the holding chain 12 attached to the end of the loading line 13, so that but a slight tautness on the hauling line 13 will serve to maintain sufficient tension on the holding chain 12 to prevent dumping of the 65 bucket. When the sheave 18 engages the stop block 19, the locking bar 81 is pulled off of the sheave 15 so that the chain 12 runs up on the larger groove thus destroying this leverage. With this leverage destroyed, but a slight slackening of the hauling line 13 gives sufficient slack to the holding chain 12 to permit free and complete dumping of the bucket. 70

While I have shown and described certain 75 embodiments of my invention, it is to be understood that it is capable of many modifications. Changes, therefore, in the construction and arrangement may be made without departing from the spirit and scope 80 of the invention as disclosed in the appended claims, in which it is my intention to claim all novelty inherent in my invention as broadly as possible in view of the prior art. 85

What I claim as new and desire to secure by Letters Patent, is:

1. In an apparatus of the character set forth, the combination of a main cable, a carriage movable thereon, a scraper bucket pivotally mounted on said carriage in the rear of the center of gravity of the bucket when loaded, a hauling line for pulling the bucket along said main cable, a block attached to the carriage, a holding chain running from the front of the bucket over said block to the hauling line, means arranged in connection with said block whereby a leverage in favor of the end of the holding chain attached to the hauling line is established when the bucket is in load-retaining position and destroyed when said bucket is in partial or complete dumping position, and means engaging said hauling line in advance of said bucket operating at a predetermined point to directly pull the holding chain over the block attached to the carriage toward the front end of the bucket. 90
2. In an apparatus of the character set forth, the combination of a main cable, a carriage movable thereon, a scraper bucket pivotally mounted on said carriage in the rear of the center of gravity of the bucket when loaded, a hauling line for pulling the bucket along said main cable, a block attached to the carriage, a holding chain running from the front of the bucket over said block to the hauling line, means arranged in connection with said block whereby a leverage in favor of the end of the holding chain attached to the hauling line is established when the bucket is in load-retaining position and destroyed when said bucket is in partial or complete dumping position, a block attached to the end of the hauling line, a block running on the main cable, a stop on the main cable in the path of movement of said last mentioned block, and a cable connected to the block running on the main cable, passing over the block on the end of 95

the hauling line, and attached to the holding chain near its point of attachment to the front end of the bucket.

3. In an apparatus of the character set forth, the combination of a main cable, a carriage movable thereon, a scraper bucket pivotally mounted on said carriage in the rear of the center of gravity of the bucket when loaded, a hauling line for pulling the bucket along said main cable, a block attached to the carriage, a holding chain running from the front of the bucket over said block to the hauling line, and means operating at a predetermined point in the travel of said bucket in connection with the pull on the hauling line to directly pull said holding chain over its block toward its point of attachment to the bucket.

4. In an apparatus of the character set forth, the combination of a main cable, a carriage movable thereon, a scraper bucket pivotally mounted on said carriage in the rear of the center of gravity of the bucket when loaded, a hauling line for pulling the bucket along said main cable, a block attached to the carriage, a holding chain running from the front of the bucket over said block to the hauling line, a block on the end of the hauling line, a block running on the main cable, a rope attached to the block running on the main cable, passing over the block on the end of the hauling line, and attached to the holding chain near its point of attachment to the front end of the bucket, and a stop on the main cable lying in the path of the block running on the main cable.

5. In an apparatus of the character set forth, the combination of a main cable, a carriage movable thereon, a scraper bucket pivotally mounted on said carriage in the rear of the center of gravity of the bucket when loaded, a hauling line for pulling the bucket along said main cable, a block attached to the carriage, a holding chain running from the front of the bucket over said block to the hauling line, a locking bar in said holding chain, said locking bar being normally in engagement with the block when

the bucket is in load-retaining position, and means operating by the pull of the hauling line at a predetermined point in the travel of the bucket to directly pull said locking bar away from said block.

6. In an apparatus of the character set forth, the combination of a main cable, a carriage movable thereon, a scraper bucket pivotally mounted on said carriage in the rear of the center of gravity of the bucket when loaded, a hauling line for pulling the bucket along said main cable, a double grooved block attached to the carriage, a holding chain running from the front of the bucket over said block to the hauling line, a locking bar in said holding chain, said locking bar being normally in engagement with the block when the bucket is in load-retaining position, and means operating by the pull of the hauling line at a predetermined point in the travel of the bucket to directly pull said locking bar away from said block.

7. In an apparatus of the character set forth, the combination of a main cable, a carriage movable thereon, a scraper bucket pivotally mounted on said carriage in the rear of the center of gravity of the bucket when loaded, a hauling line for pulling the bucket along said main cable, a block attached to the carriage, a holding chain running from the front of the bucket over said block to the hauling line, a locking bar in said holding chain, said locking bar being normally in engagement with the block when the bucket is in load-retaining position, a block on the end of the hauling line, a block running on the main cable, a rope attached to the block running on the main cable, passing over the block on the end of the hauling line and attached to the holding chain below the locking bar, and a stop on the main cable lying in the path of the block running on the main cable.

In witness whereof, I have hereunto set my hand and seal this 10th day of January, 1924.

JOHN W. PAGE. [L.S.]
